US0D1041057S

(12) **United States Design Patent** (10) **Patent No.:** **US D1,041,057 S**
(45) **Date of Patent:** **** Sep. 3, 2024**

(54) **SCONCE**

(71) Applicant: **Williams-Sonoma, Inc.**, San Francisco, CA (US)

(72) Inventor: **Rachel Kaufman**, San Rafael, CA (US)

(73) Assignee: **Williams-Sonoma, Inc.**, San Francisco, CA (US)

(**) Term: **15 Years**

(21) Appl. No.: **29/846,384**

(22) Filed: **Jul. 15, 2022**

(51) **LOC (14) Cl.** **26-05**

(52) **U.S. Cl.**

USPC **D26/87**

(58) **Field of Classification Search**

(74) Attorney, Agent, or Firm — Cook Alex Ltd.

(57) **CLAIM**

The ornamental design for a sconce, as shown and described.

DESCRIPTION

FIG. 1 is a front perspective view of a sconce;

FIG. 2 is a bottom perspective view of the sconce;

FIG. 3 is a front elevational view of the sconce;

FIG. 4 is rear elevational view of the sconce;

FIG. 5 is a left side elevational view of the sconce;

FIG. 6 is a right side elevational view of the sconce;

FIG. 7 is a top plan view of the sconce; and,

FIG. 8 is a bottom plan view of the sconce.

The broken line portions of the drawings are included to show portions of the article that form no part of the claimed design and represent environmental structure only.

1 Claim, 8 Drawing Sheets
